UNITED STATES PATENT OFFICE.

HECTOR LE DOUX, OF WORCESTER, MASSACHUSETTS, AND JAMES KARMI DALKRANIAN, OF WEEHAWKEN HEIGHTS, NEW JERSEY; SAID DALKRANIAN ASSIGNOR TO UNITED STATES PERSIAN CARPET COMPANY, A CORPORATION OF NEW YORK, AND SAID LE DOUX ASSIGNOR TO CROMPTON & KNOWLES LOOM WORKS, A CORPORATION OF MASSACHUSETTS.

WOVEN FABRIC.

1,077,227.

Specification of Letters Patent. Patented Oct. 28, 1913.

Application filed February 12, 1912. Serial No. 677,037.

To all whom it may concern:

Be it known that we, HECTOR LE DOUX and JAMES K. DALKRANIAN, citizens of the United States, residing, respectively, at 5 Worcester, in the county of Worcester and State of Massachusetts, and at Weehawken Heights, in the county of Hudson and State of New Jersey, have jointly invented certain new and useful Improvements in Woven 10 Fabrics, of which the following is a specification.

Our invention relates to woven textile fabrics, and more particularly fabrics of the eastern, or Persian type, automatically 15 manufactured on looms of the class shown and described in U. S. Letters Patent, No. 858,963. In said class of looms, the tuft yarns for forming the pile are inserted between the warp threads, and interwoven 20 therewith by carrying the tuft yarns around the warp threads to form Persian knots, or the like, which are firmly held in the fabric by filling threads inserted into the shed by a filling needle or carrier.

25 In the manufacture of tufted fabrics on the class of looms referred to, the filling threads which are put into the shed, are ordinarily stretched and taut, and cause, on the crossing of the warp threads, not only a 30 considerable shrinking of the fabric, but also prevent the pile from being beaten up closely and evenly by the lay, which causes an uneven appearance of the fabric, and consequently affects the commercial value of the 35 same.

The object of our invention is to provide a woven fabric of the type referred to, of improved construction.

In our woven fabric, we use a specially 40 made filling, which, with the ordinary filling, will be put into the shed by the filling needle or carrier, to bind the pile or tuft yarn. The specially made filling, which we term in this instance "extensible" filling, is 45 preferably made of soft yarn, which with a number of threads loosely twisted together in one or more strands, are twisted around one or two fine center threads or strands, which are strong enough to hold the extensible 50 filling at its normal length, while it is being put into the shed by the filling needle or carrier. As soon as the warp threads are

crossed, and the lay beats up, a severe strain is brought upon the filling, which causes the fine center threads or strands to break at 55 several places, and allows the loosely twisted outer yarn to be extended, to an amount of half as much or more than the normal length of the ordinary filling. By means of this extensible filling, in connection with the 60 ordinary filling, the tufted fabric is prevented from shrinking, and an even and close beating up of the pile is obtained. Beside the extensible filling, the ordinary filling is put into another shed, which does not require as much stretching of the filling. 65

Our invention consists in our improved construction of woven fabrics of the type referred to, and more particularly in using two different fillings, one an extensible filling, 70 and the other the ordinary filling, which fillings are put into the sheds by a filling needle or carrier, as will be hereinafter described.

We have shown in the drawings and described herein, mechanism for making our 75 improved woven fabric, which mechanism, according to the weave, automatically selects the extensible filling, or the ordinary filling, to be used, as will be hereinafter described.

We have only shown in the drawings a detached portion of a tufted fabric loom, with our improvements combined therewith, sufficient to enable those skilled in the art to understand how our improved woven fabric is made. 80

85 Referring to the drawings:—Figure 1 is a front view of a detached portion of the lay, and the needle motion, looking in the direction of arrow *a*, Fig. 2. Fig. 2 is a plan view of the parts 90 shown in Fig. 1, looking in the direction of arrow *b*, same figure. Fig. 3 is a section, on line 3, 3, Fig. 1, looking in the direction of arrow *c*, same figure. Fig. 4 shows, on an exaggerated scale, a transverse cross section 95 of the fabric, with the two different fillings inserted. The inner broken center threads of the extensible filling are shown by broken lines at the right. Fig. 5 illustrates, on an enlarged scale, a detached portion of one end 100 of the extensible filling, with one end un-twisted, and, Fig. 6 shows a tension mechanism for the extensible filling.

In the accompanying drawings, 1 is a por-

tion of the lay, having the reed 2 thereon, with dents through which the warps 3 pass, see Fig. 2, from the rear of the loom.

4 is the tufted fabric, which in this instance is woven with the pile 5, having its ends projecting below the lower surface of the fabric.

6 is the filling needle or carrier, guided upon a guide roll 7, which is rotatably mounted on a shaft or stud 8 on a stand 9. A reciprocating movement is communicated to the filling needle 6 at predetermined times, from mechanisms on the loom, not shown.

15 Two horizontally extending levers 11 and 12, have their hubs 11' and 12', see Fig. 2, pivotally mounted on a stud 10, in a boss 9", on an arm 9' of a stand 9. The lever 11 has adjustably attached to its rearwardly extending arm, see Fig. 3, a stud 13, to which is pivotally connected the upper end of a downwardly extending connector or rod 14, which rod is operated by mechanism on the loom, not shown. The oppositely extending 20 arm on the lever 11 is provided with a boss 11" at its end, to which is adjustably secured the upwardly extending thread holder 15, provided with a thread-eye 15', through which in this instance the ordinary filling 16 passes from a spool, not shown, to the fabric.

At predetermined times the lever 11 is operated, and on the downward movement of the thread holder or guide 15, the filling 16 is moved downwardly and enters the 25 open slot 6' in the end of the filling needle 6, and the movement of said filling needle 6 carries the filling 16 into the shed. The second lever 12 has a bolt 17 adjustably secured thereto at its outer end, to which is 30 pivotally connected the upper end of a downwardly extending connector rod 18, which rod is operated by mechanism on the loom, not shown. The opposite arm of the lever 12 is provided with a boss 12" at its 35 end, in which is adjustably secured the upwardly extending thread holder 19, which has a thread-eye 19', through which in this instance the extensible filling 20 passes from the delivery spool to the fabric. The downward movement of the arm 12, and the 40 thread holder 19, at predetermined times, causes the extensible filling 20 to enter the open slot 6' in the end of the filling needle 6, see Fig. 1, and the movement of said filling 45 needle 6 carries the filling 20 into the shed.

The two fillings 16 and 20 are preferably carried alternately into the shed, according to the operation of the loom. The extensible filling 20, as shown in Fig. 5, is made in this 50 instance of soft twisted threads 20', which are loosely twisted in this instance in two strands around the interior or center fine threads 20''. On the crossing of the warp threads 3, on the beating up of the lay, the 55 fine threads 20'' will be broken at several

places, as shown at the right in Fig. 4, and allow the outer filling threads 20' to extend or stretch, to bind the warp threads, as shown in Fig. 4, without any shrinking of the fabric, and consequently any uneven appearance of the fabric.

To prevent the extensible filling from unrolling too fast, and to hold the filling tight as long as it is not in use some tension device is provided, one style of which is shown in Fig. 6. A spool 21, see Fig. 6, is rotatably supported on a downwardly hanging rod 22, in a conical receptacle 23, which is secured to a frame-work 24 at the side of the loom. The filling 20 passes from the spool 21 through an eye 23' in the bottom of the receptacle 23, and under the end of a tension spring blade 25, which is secured at one end, in this instance within a trough or guide 26. The extensible filling 20 passes through a 85 thread-eye 27, and under the hook eye 28' on an upwardly extending wire 28, and then through an eye 29, and tube 30 supported on the frame 24, see Fig. 6. From the tube 30, the extensible filling 20 passes to the thread 90 holder eye 19', above described. On the insertion of the extensible filling 20, the hook wire 28, pivotally attached at its lower end to the end of a lever 31, is raised through mechanism on the loom, not shown, 95 to the position shown by broken lines in Fig. 6. At the same time, the tension spring 25 will be raised from the extensible filling 20, by the downwardly extending rod 32, which has its lower end pivotally connected to the 100 end of a lever 33, which is operated by a cam on the loom, not shown, at predetermined times. A helically coiled contraction spring 34 attached at one end in this instance to a boss on the rod 32, and at its 105 other end to the frame 24, acts to yieldingly move downwardly the lever 33 to hold the roll thereon in engagement with the operating cam.

It will be understood that the manufacture of our improved woven fabric, with an extensible filling, in connection with an ordinary filling, may be carried out by different mechanisms, and we do not limit our invention to the particular mechanism 110 shown in the drawings and above described.

We have described herein our improved woven fabric as a tufted fabric, but it will be understood that we do not limit our invention to tufted fabrics, as our improvements in woven fabrics may be used in connection with other classes of fabrics, in which the crossing of the warps and the beating up of the lay, puts too much tension on one of the fillings, enough to cause shrinking 125 of the fabric, unless the filling extends or stretches.

Our extensible filling may be described as made up of threads of different tensile strength, some of said threads to be extend- 130

ed without breaking, and the others to be broken, as the fabric is woven.

Having thus described our invention, what we claim as new and desire to secure by Letters Patent is:

1. In tufted fabrics of the class referred to, warp threads, tuft yarns wrapped around the warp threads, and forming the pile, and filling threads binding the pile, comprising 10 in ordinary filling, and a filling having one or more center non-stretchable threads, forming a substantial straight core or center, and threads wrapped or twisted around the center core, and adapted to stretch or extend 15 lengthwise when the center threads break.
2. A tufted pile fabric, comprising warp threads, pile yarns inserted between and looped around one or more of the warp 20 threads, filling threads, comprising an ordinary filling, and an extensible filling, said extensible filling comprising a broken thread or threads, and extended strands wrapped or twisted around said broken 25 threads.

3. A tufted pile fabric, comprising warp threads, pile yarns inserted between and looped around one or more of the warp threads, filling threads substantially non-extensible, and other filling threads, comprising a substantially straight core or center adapted to be broken, and threads wrapped or twisted around the center core and adapted to stretch or extend lengthwise when the center breaks. 30

4. A woven fabric, comprising warp threads, and substantially non-extensible filling threads, and other filling threads comprising a substantially straight core or center adapted to be broken, and threads 40 wrapped or twisted around the center core, and adapted to stretch or extend lengthwise when the center breaks.

HECTOR LE DOUX.
JAMES KARMI DALKRANIAN.
